Patented Nov. 28, 1911.

UNITED STATES PATENT OFFICE.

WILLIAM NOVILLE, OF CLEVELAND, OHIO.

AUTOMATIC GATE FOR RAILWAY-CROSSINGS.

1,009,927.

Specification of Letters Patent. Patented Nov. 28, 1911.

Application filed April 8, 1911. Serial No. 619,682.

To all whom it may concern:

Be it known that I, WILLIAM NOVILLE, citizen of the United States, residing at Cleveland, in the county of Cuyahoga and State of Ohio, have invented certain new and useful Improvements in Automatic Gates for Railway-Crossings, of which the following is a specification.

My invention relates to automatic gates for railway crossings, and is an improvement in the gate described and shown in my pending application, Serial Number 569,867, and the improvement consists in the construction of gate and its operating means substantially as herein shown and described and more particularly pointed out in the claims.

My object is to station a gate at the crossings of railways, steam or electric, and cause automatic lowering thereof upon the approach and passage of a car or train of cars. Obviously, such automatic lowering of a gate might in itself be dangerous, either by striking or trapping a person or vehicle at the crossing, and therefore my object also is to provide a gate and operating means therefor which will reduce this danger to a minimum.

In the accompanying drawings, Figure 1 is a side elevation and sectional view of my improved gate, and Fig. 2 is a diagram of an electrical railway and a trolley car, including the electrical connections leading therefrom to the operating motor for the gate.

As shown, the gate A is of the two-arm type having segment-gear engagement for co-joint operation and wherein the longer arm 2 is adapted to extend over the road or street and the short arm 3 over the sidewalk. The segment portions 4 of each arm are rotatably mounted within or upon a casting 5, and a counterweight 6 on an outside arm 7 rigid with the axis 8 of the gate 2 serves as usual to counter-balance both the gate arms for ease of operation. These features are old, but the gate as improved further comprises a shouldered hinge connection 9 for each arm 2 and 3, respectively,—the hinge being on top to permit free and independent backfolding of the arms in respect to the segment portion 4. Thus, when the arms are being lowered and an object is encountered by either arm, no ill results will follow either to the object or to the

mechanism for operating the arm. Briefly, the arm will yield or come to a standstill; whereas, the segment portions 4 and counterweighted arm 7 will be undisturbed in describing maximum arc movements. This is important for the reason that operations are dependent upon a power device represented herein as an electric motor 10 and which acts more or less rapidly when placed in an electric circuit. Thus, when the motor 10 is energized, rotation of its armature shaft 11 is immediate and complete to wind a cable 12 about a reel 14 on the shaft 11 and thereby lower the gate by a pull on a right angled bracket 15 which is secured to the segment portion 4 of the arm 3,—the arc movement being relatively short as indicated by full and dotted lines of the parts in Fig. 1. The lowered position is sustained for a greater or less period of time, or in other words, the pull by the motor continues to hold the gate down until the train or car has passed the crossing and motor 10 again placed out of electric circuit. Then, counterweight 6 comes into action to raise the gates, unwinding the cable 12 from the reel 11 by this return movement.

A quick-acting power device is of advantage if for no other reason than that direct and simplified operating connections may be made between the gates and motor, thereby eliminating back gearing and the like; but obviously, if the gates are lowered too quickly, serious results might follow. Therefore, I hinge the arm of the gate to the segment portions 4 and also provide a device B to automatically control the speed of descent of the arm after the motor 10 has acted and performed its function and is at a standstill. This device B comprises an air cylinder 16 pivotally secured at its bottom end to a lug 17 on the casing 5, and having a piston or plunger 18 slidably confined therein with a stem 19 pivotally secured at 20 to the bottom of the arm 2 approximately opposite the hinge connection 9. A valve 21 at the bottom end of cylinder 16 controls the exit of air from the cylinder whereby the speed of descent of the plunger 18 and arm 2 may be regulated. In operation, the segments 4 are rotated to their full extent by a comparatively quick action of the motor 10, whereas the arm 2 in this movement is checked temporarily in its descent and is unfolded—the arm 2 and the seg-

ment portion 4 approximately assuming the relative positions shown in dotted lines Fig. 2. Then the arm 2 will gradually descend under control of the device B. A coiled spring 5 resting upon the piston 18 within the cylinder 16 is adapted to be compressed upon uplift of the gate 2, thereby cushioning the gate in this movement and also affording a quick down pull of the gate at the beginning of its descent, and before a slow or checked descent is required. Although not shown, it is obvious that the gate arm 3 may also be similarly provided with a checking device B, and that all the operating parts may be inclosed within the casing 5. The arm 3 may also be omitted altogether. Furthermore, any preferred and acceptable means may be used for temporarily placing the motor 10 in an electrical circuit by a car or train of cars passing over a given section of track at a crossing.

Either steam or electrical railways may be equipped with my improved gates, but in view of the need of such safeguards for cross-country electric lines, I show means particularly adapted for use with an electric trolley system. Thus referring to Fig. 2, a trolley car C is shown having a trolley 21 engaged with a trolley wire 22. The track is represented by 23, and a duplicate set of double switches or electric-circuit establishing devices D are arranged at separated points along the line of the trolley wire 22, one at either side of the crossing which may be assumed to be located at x-x. The switches D are electrically connected in parallel and are insulated from the trolley wire 22, which is electrically connected with the motor 10 by a wire 24. A return wire 25 from the motor 10 connects with an armature 26 of a relay R, which when energized closes the return circuit over wires 27 and 28 leading to the rail 23. The relay R is energized when the trolley wheel 29 contacts with a member 30 of either switch D, the current from the trolley wire passing over line 31, through coils 32, and over return wires 27 and 28 to the rail. The car C is now on a section or block of track represented by 23' and which section or block is insulated from the remainder of track. The car itself then establishes a circuit over trolley-wire 22, wire 24, armature 33 of a second relay S, wire 34 and coil 35 of relay R, and thence to rail wire 28. This establishes a closed circuit for the motor 10 as long as the car is in the section or block 23'. By this means, the gates are immediately lowered and remain down until the trolley wheel 29 contacts with the member 30 of the switch D and thereby establishes a temporary circuit over line wire 37, coils 38 of relay S, rail wire 28, and through a ground generator and to the trolley wire. The relay S is then thus energized for the in-

stant, its armature 33 is attracted and the circuit over the wire 24 to the coils 35 of the relay R is interrupted, which releases the armature 26 and breaks the motor circuit over the return wire 27. Both relays are now deenergized and the gates will be lifted by their counterweight 6, the motor being out of circuit.

It must be understood that no damage to motor 10 will occur after the gate is lowered, for the reason that a full-load start machine is used in which the armature continues to rotate after the shaft is stopped by overload—a common type of motor. Obviously, the use of this type of motor is not arbitrary as any other suitable electrical power device may be used to operate the gate. Now, again referring to coils 35, these coils will not attract armature 26 and close the operating circuit of the gates in the normal condition of the apparatus on account of the particular type of relay used. Thus the coil consists of many noninductive turns of copper wire, therefore, not giving this coil the pulling strength on the armature to draw it over the relatively wide air-gap used. On the other hand the coil or winding which pulls the armature has many turns of copper wire or inductive windings, giving the needed pulling strength to attract the armature. The same result may be obtained in other ways, and any suitable device and arrangement of circuits may be used to place the operating motor in and out of circuit to close and open the gates without affecting the invention herein shown and claimed.

What I claim is:

1. In gates for railway-crossings, a jointed arm comprising a rotatable member and an outer portion hinged thereto, means to lower said jointed arm, and means to temporarily retard descent of the outer portion of said arm upon downward movement of the rotatable member.

2. In gates for railway-crossings, a jointed arm having a rotatable support, a power device to lower said arm, and a device to back-fold and temporarily hold the outer jointed portion of the arm in raised position for gravity descent upon rotatable movements of said support.

3. In gates for railway-crossings, a counterweighted arm rotatably mounted and hinged to unfold during lowering movements thereof, a power device to lower said arm, and a retarding device to temporarily maintain the hinged portion of said arm in uplifted position upon lowering movements of its rotatable portion, said device embodying means to effect gradual gravity-lowering of said hinged arm portion.

4. In gates for railway-crossings, a counterweighted arm comprising a rotatable member having an arm hinged thereto, a motor and operating connections to lower

said arm and member together, and an air cylinder and plunger to unfold said arm and control its descent.

5. In gates for railway-crossings, a set of 5 geared members rotatably mounted and having arms pivotally connected therewith to fold and unfold, a counterweight for said arms, a motor operatively connected with said members to lower the same, and a dash- 10 pot device for said arms to unfold and control lowering thereof.

6. In automatic gates for railway-crossings, a jointed arm comprising a rotatable member and a hinged outer portion, a re- 15 tarding and speed-controlling device to temporarily hold the said outer portion in vertically inclined position upon a complete movement of said rotatable member, and power operative means to operate said arm, 20 in combination with means at the crossings adapted to control operation of said power means by the passing of a railway-car.

7. In automatic gates for railway-crossings, power operative means, devices at

either side of the crossing to control said 25 means by the passing of railway cars, in combination with a gate comprising a rotatable member operatively connected with said power means, an arm hinged to said member, and a device connected with said 30 arm to back-fold and uplift said arm during maximum arc movements of said rotatable member and comprising means to gradually permit a gravity drop of said arm to a horizontal position.

35 8. In gates for railway-crossings, a counterweighted member having a gate-arm hinged thereto, means to rotate said member to lower said arm, and an air cylinder and plunger and a spring to unfold and control 40 said arm in its descent.

In testimony whereof I affix my signature in presence of two witnesses.

WILLIAM NOVILLE.
